ATTORNEYS

UNITED STATES PATENT OFFICE.

JOSEPH MARTIN BRANDT, OF BELLEVUE, IOWA.

TOOL.

1,417,492.

Specification of Letters Patent. Patented May 30, 1922.

Application filed November 24, 1920. Serial No. 426,166.

To all whom it may concern:

Be it known that I, JOSEPH M. BRANDT, a citizen of the United States, and a resident of Bellevue, in the county of Jackson and 5 State of Iowa, have invented certain new and useful Improvements in Tools, of which the following is a specification.

My invention is an improvement in tools, and has for its object to provide a device 10 of the character specified, especially adapted for pressing taper battery terminals from battery posts, without throwing strain upon the cover that might be liable to injure the same.

15 In the drawings:

Figure 1 is a front view of the improved tool,

Figure 2 is an end view, looking at one end,

20 Figure 3 is a partial end view looking at the other end,

Figures 4 and 5 are sectional views of the battery posts and terminals showing the manner of using the device.

25 As is known, the terminals in batteries must necessarily be snugly drawn into the battery post in order to insure a good connection. When it becomes necessary to remove these terminals, it is difficult to do so 30 without injuring the battery cover.

As shown in Figures 4 and 5, the post 1 has a tapering opening 2, into which the tapering terminal 3 is received, and a screw 4 is passed through the small end of the 35 opening 2 and engaged in an axial threaded opening 5 in the terminal.

By turning this screw, the terminal may be drawn tightly into the tapering opening, to insure a good electrical connection as 40 shown in Figure 4. In order to facilitate the removal of these terminals, and to avoid injury to the battery cover, I provide the device shown more particularly in Figure 1 and consisting of jaws 6 and 7, each of 45 which is provided intermediate its ends with a threaded opening for receiving a screw 8.

This screw has a winged head as shown, and the jaw 6 is provided at one end with

a threaded bearing 9 for receiving a similar screw 10. The jaw 7 has at the end adjacent to the screw 10 a step bearing 11, and the screw 10 has a head 12 which is received in this bearing.

It will be evident that by turning the screws in the proper direction, the jaws may 50 be moved toward and from each other to vary the space between the same. By holding the screw 10 and turning screw 8 the gripping ends of the jaws may be moved toward or from each other.

In order to permit the jaws to engage the head of the screw 4 and to engage the post on opposite sides of the terminal, one of the jaws, the jaw 6, in the present instance, is forked at the end remote from the screw 60 10, the arms of the fork being indicated at 13.

In operation, to loosen the terminal, the screw 4 is first turned a few turns, as shown 70 in Figure 4. Then the tool is engaged by placing the engaging end of the jaw 7 on the head of the screw, and the arms 13 of the jaw 6 against the post, one arm being on each side of the terminal. Now the jaws 6 and 7 are forced toward each other, 75 and it will be obvious that the terminal will be loosened as shown in Figure 5, without any strain on the post or on the cover.

I claim:—

A tool for removing terminal connections from battery posts comprising a pair of jaws having their intermediate portions 80 interiorly screw threaded, a screw threaded through the intermediate portions of said jaws, a second screw threaded through the terminal portion of one of the jaws and engaged with the terminal portion of the other jaw, the forward terminal portions of 85 one of the jaws being straight and adapted for engagement with the screw of the terminal connection and the terminal portion of the other jaw being forked to straddle the terminal connection and engage the battery posts on opposite sides of the terminal connection.

JOSEPH MARTIN BRANDT.
